2 Sheets-Sheet 2

UNITED STATES PATENT OFFICE.

MALCOLM HARD, OF FLUSHING, NEW YORK, ASSIGNOR TO THE SUPERHEATER COMPANY, OF NEW YORK, N. Y., A CORPORATION OF DELAWARE.

LOCOMOTIVE-FEED-WATER-HEATING SYSTEM.

Application filed August 19, 1924. Serial No. 732,907.

This invention relates to locomotive feed water heating systems in which the feed water is heated by the exhaust steam from the locomotive in that type of heating system known as the closed type. In such systems, provision must be made to dispose of the condensate formed in the heater by the condensing of the exhaust steam. This condensate may be returned to the boiler by leading it into the suction line of the feed water pump, which forms a part of these systems; or it may be discharged to the track, or it may be returned to the tender. While the return of the condensate to the boiler is preferable from the standpoint of economical operation, such return is objectionable under certain conditions, as for example, when the engine is working hard with a long cutoff and particularly when the pump at the same time is delivering water to the boiler at a slow rate. Under these conditions, due to the high temperature of the feed water, steam will be formed in the suction line of the pump and will interfere with the proper functioning thereof. The discharge of the condensate to the track is not always practicable in certain locations, as for example, in stations.

It is the principal object of this invention to provide a new and improved construction in feed water systems of the type hereinbefore referred to by means of which the condensate may be selectively directed either to the tracks, or to the suction line of the pump to mingle with the feed water from the tender.

Another object of my invention is to provide a new and improved construction of a duplex valve particularly adapted for use with a feed water heating system of the type hereinbefore set forth.

These and further objects will be apparent to those skilled in the art to which my invention appertains from the following more detailed description and from the accompanying drawings forming a part hereof and wherein an example of the invention is shown without defining its limits.

As shown in the drawings Fig. 1 is a side elevation showing, somewhat diagrammatically, an application of my invention to a locomotive; the locomotive parts being shown in dotted lines; Fig. 2 is an enlarged sectional detail of the duplex valve taken

on the line 2—2 of Fig. 3; Fig. 3 is a section on the line 3—3 of Fig. 4; Fig. 4 is a section on the line 4—4 of Fig. 3, and Fig. 5 is an enlarged detail of the connection of the duplex valve to the suction line of the pump.

As shown in Fig. 1 the feed water heater A is supplied with exhaust steam through the pipe B, connected with the exhaust line at any suitable point. The feed water is drawn from the tender C by the pump D through the suction pipe E and is delivered to the heater A by the pipe F. After passing through the heater the water flows to the boiler through the pipe G which is provided with the usual check valve. The condensate formed in the feed water heater by the cooling of the exhaust steam is drained off through the pipe H. The above arrangement is the usual equipment for this type of feed water heating system and has merely been shown diagrammatically.

Suitably connected with the pipe H is a duplex valve K, the casing 10 (see Figs. 2 to 4) of which is provided with inlet 11 which furnishes communication between the trap and a distributing chamber 12 formed in said valve casing. A pair of valves 13, 14 which are mounted within said distributing chamber are adapted to be forced into contact with the valve seats 15 and 16, by mechanism to be hereinafter described, to shut off communication between the chamber 12 and either of the outlets 17 and 18 respectively. The outlet 17 has connected thereto a pipe 19 terminating in a jet nozzle 19^a, which projects into the suction line E of the pump, and the outlet 18 has connected thereto a conduit 20 which leads to the track.

Preferably each of the valves 13 and 14 is formed integral with and between the ends of a guide rod 21. The lower end of each guide rod 21 passes slidably through a bearing 22 formed in a web 23 preferably cast integral with the valve casing 10, while the upper end of each valve rod is slidably received within a central bore of a bonnet 24 formed upon a cap 25, removably secured by its reduced screw threaded end 26 in the valve casing. Each valve rod is provided between its ends with a pair of spaced annular shoulders or flanges 27 with which the rounded ends 28 of the yoke arms of a tumbler lever 29 engage for actuating the

valves. The tumbler lever 29 is provided with a central boss 30 having a central aperture of rectangular cross section which is fitted upon a similarly shaped portion of a 5 tumbler shaft 31. The tumbler shaft 31 is rotatably mounted in suitable bearings 33 and 34 formed respectively in a removable cap 35 and the valve casing 10.

As the outlet passage 17 of the duplex 10 valve is connected to the pipe 19 which leads to the pipe E leading from the tender, while the passage 18 has connected thereto the pipe 20 leading to the track, it will be understood that means must be provided for 15 preventing both valves 13, 14 from remaining unseated at the same time for if both valves were to remain open, water from the tender would drain through the duplex valve and flow out to the track. A suitable construction for insuring that one of the valves 13, 14 will always be seated is as follows:

One end of the tumbler shaft 31 projects through the valve casing 10 and terminates in a wing portion 36 which has at its extremities a pair of laterally projecting lugs 37. Mounted in a suitable bearing 38 provided in a housing 39 and in axial alignment with the tumbler shaft 31 is an actuating shaft 40 one end of which projects outwardly of the housing 39 through a stuffing box 41 and has secured thereto a lever 42. The lever 42 has connected thereto an actuating rod 43 which extends to any conveniently accessible point within the locomotive cab. 25 The other or inner end of the shaft 40 has formed integral therewith a crank arm 44 which is located within the housing 39 between the lugs 37 of the wing portion 36 of shaft 31. The outer end of crank arm 44 is pivotally secured as by the pin 45 within the yoke end 46 of a spring rod 47. The lower cylindrical end of said spring rod is slidably received within a bearing 48 supported for oscillation by the trunnions 49, 30 mounted within the bearings 50 and 51 formed respectively in the housing 39 and a removable cap 52. A coiled spring 53 which surrounds the spring rod 45 has its upper and lower ends respectively in contact with 35 the shoulder formed by the upper yoked end of the spring rod and the upper face of the bearing 48.

The manner of operation is as follows: Under normal operating conditions the duplex valve is adjusted so that the condensate from the feed water heater is led to the suction line E through the outlet 17 and pipe 19, the valve parts at this time being in the dotted line positions shown in Figs. 2 40 and 4. If for any reason it becomes necessary or desirable to direct the flow of the condensate from the suction line of the pump to the track, the actuating rod 43 is operated to move the shaft 40 and associated parts from the dotted to the full line posi-

tions shown in Figs. 2 and 4. This movement of the shaft 40 will move the crank arm 44 out of contact with the left hand lug 37 of the wing portion 36 of tumbler shaft 31 and into contact with the right hand lug 37, thus causing the tumbler shaft 31 to be rotated in a counter-clockwise direction as viewed in Fig. 4, or clockwise as viewed in Fig. 2, to move the valve 14 off its seat 16 and the valve 13 towards its seat 15. 75

It will be noted that the lugs 37 are so spaced from each other that the crank arm 44 does not contact with the right hand lug 37 until after the pivotal connection 45 of the crank arm and spring rod 47 has 80 passed its dead center, therefore when the crank arm engages either lug 37 the full force of the spring 53 is exerted upon the tumbler shaft and its associated parts so as to insure the movement thereof to their extreme positions, in which either the valve 13 or the valve 14 is held seated firmly upon its respective seat. It will be also noted that the caps 25, being removable, permit ready access to the valve in addition to serving 85 as guides for the valve rod 21. It will further be noted that the actuating shaft 40 with the parts 44 and 47, etc., connected therewith are mounted entirely within the housing 39 and form therewith an unitary 90 assembly which can be detached from the valve casing 10 and the parts mounted therein by removing the bolts 55 thus providing a construction which enables the parts to be assembled easily or to be taken apart readily 95 for inspection or repairs.

It is to be understood that while the lost motion connection formed by the crank arm 44 of shaft 40 and wing portion 36 of shaft 31 between the actuating rod 43 and the valves 13 and 14 as shown is a satisfactory embodiment of my invention, the principles herein disclosed are not limited to the specific details of said connection, or the manner of mounting the valves, but that various 100 changes and modifications may be resorted to without departing from the spirit of my invention.

I claim:

1. In a locomotive feed water heating system, a feed water heater, means for supplying steam to said heater, a drain line for withdrawing condensate from said heater, a source of feed water, a pump and feed line for conducting feed water from said source to said heater, a discharge line, a three-way fitting connecting said drain line with said discharge line and with said feed line between the source of feed water and the pump, valve means in said fitting for selectively establishing a communication between said drain line and said discharge line while closing communication between the feed line and the drain and discharge line, or for establishing communication between said drain 115

120

125

130

line and said feed line while preventing communication between said discharge line and said feed and drain lines.

2. In a locomotive feed water heating system, a feed water heater, means for supplying steam to said heater, a drain line for withdrawing condensate from said heater, a source of feed water, a pump, a feed line having a portion leading from said source 10 to said pump and a second portion leading from said pump to said heater, a valve casing connected to the drain line and the first mentioned portion, a line leading from said casing to discharge on the track, valve means 15 arranged in said casing to selectively permit flow from the drain line to the first mentioned feed line portion while preventing flow to the discharge line from the feed and drain lines or to permit flow to the discharge 20 line from the drain line while preventing flow from the feed line to the drain and discharge lines.

3. In a locomotive feed water heating system, a feed water heater, means for supplying steam to said heater, a drain pipe for withdrawing condensate from said heater, a source of feed water, a pump and a feed line connected with said source for supplying feed water from said source to said heater 25 and a valve casing connected with said drain pipe, said valve casing having a pair of outlets, one connected with said feed line and the other to discharge the condensate from said pipe to the track, a pair of valves 30 mounted within said casing for controlling said outlets and means for preventing both of said valves from simultaneously remaining 35 in open positions.

4. In a locomotive feed water heating system, comprising a feed water heater, means for supplying steam to said heater, a drain line for withdrawing condensate from said heater, a source of feed water, fluid propelling means, a feed line including said propelling means for forcing feed water from said source to said heater, and a discharge line associated with said drain line; the combination of means interconnecting said drain line, said discharge line, and said feed line, 45 and valve means in said interconnecting means for selectively cutting off communica- 50

tion between the drain and discharge lines while permitting flow from the drain to the feed line, or cutting off communication between the drain and feed lines while permitting flow from the drain to the discharge line thereby preventing substantial flow of water from said source through said discharge line at any time. 55

5. In a locomotive feed water heating system, comprising a feed water heater, means for supplying steam to said heater, a drain line for withdrawing condensate from said heater, a source of feed water above the drain line outlet, fluid propelling means, a feed line including said propelling means for forcing feed water from said source to said heater and a discharge line associated with said drain line; the combination of a three-way fitting interconnecting said drain line, 60 discharge line, and feed line, valve means in said fitting for selectively cutting off flow to the discharge line from the feed line while permitting flow from the drain line to the discharge line or for permitting flow to 65 the feed line from the drain line, while preventing flow to the discharge line from the drain and feed lines, and means for actuating said valve means including a spring adapted to prevent said valve means from 70 remaining in a position intermediate its limits of movement. 75

6. In a locomotive feed water heating system, a feed water heater, means for supplying steam to said heater, a drain pipe for 80 withdrawing condensate from said heater, a pump and feed line for supplying feed water to said heater, a duplex valve connected with said drain pipe, said valve having a pair of outlets one connected with said 85 feed line and the other to discharge the condensate from said pipe to the track, a pair of valves for controlling said outlets, and means including a lost motion connection for simultaneously actuating both of said valves 90 and a spring to prevent said connection from remaining in a position intermediate its limits. 95

In testimony whereof I have hereunto set my hand.

MALCOLM HARD.
